CLAIM

The ornamental design for a lead paddle as shown and described.

DESCRIPTION

FIG. 1 is a front, top, and right perspective view of a first embodiment of a lead paddle, showing our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a front, top, and right perspective view of a second embodiment of a lead paddle, showing our new design; FIG. 8 is a front elevation view thereof; FIG. 9 is a rear elevation view thereof; FIG. 10 is a right side elevation view thereof; FIG. 11 is a left side elevation view thereof; and, FIG. 12 is a top plan view thereof. The broken lines of even length shown in the drawings illustrate portions of the lead paddle that form no part of the claimed design.
